UNITED STATES PATENT OFFICE.

ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

CASKET-HANDLE.

1,229,650.

Specification of Letters Patent. Patented June 12, 1917.

Application filed June 29, 1916. Serial No. 106,641.

To all whom it may concern:

Be it known that I, ALBERT A. PAGE, a citizen of the United States, residing in East Haven, county of New Haven, and 5 State of Connecticut, have invented certain new and useful Improvements in Casket-Handles, of which the following is a full, clear, and exact description.

This invention relates to casket or box 10 handles, and more particularly to those constructed of sheet metal where a U-shaped bail is inserted at its ends through the end portions of a socket plate and secured in place by pivot pins or trunnions 15 located at the back of the plate.

The primary object of my invention is to provide a very simple, strong construction, and more especially it is my object to provide improved means for locking 20 each pivot pin or trunnion in place in a suitable seat formed at the rear surface of the socket plate.

Another object of my invention is to provide a handle of the type indicated, which 25 can be very readily manufactured and assembled.

To these and other ends, the invention consists in the novel features and combinations of parts to be hereinafter described 30 and claimed.

In the accompanying drawing,

Figure 1 is a front elevation of a casket handle embodying my invention;

Fig. 2 is an end elevation thereof;

35 Fig. 3 is a rear elevation of the handle;

Fig. 4 is a section on line 4—4 of Fig. 3;

Fig. 5 is a fragmentary front elevation 40 of the socket plate, with the bail in the raised position and shown in section; and

Fig. 6 is a detail of one of the bridge pieces.

In the drawing I have shown my improvements as applied to a casket or box handle having a sheet metal bail or handle 45 proper 10 attached at the respective ends to a plate 11, which is adapted to be secured to the casket or box in the usual manner. The hanger arms 12 of the bail, viz., the side portions thereof, are shown 50 as of semi-tubular cross-section. At its upper end each hanger arm is cut to form a fork, the respective tines or branches of which are constituted by plates or exten-

sions 13 integral with the respective side walls of the arm. Each of the plates 13 55 extends through a narrow slot 14 cut through the sheet metal wall of the socket plate 11 and directed vertically with respect to said plate. The plates 13 extend through the respective slots 14 so that a 60 substantial part of each plate is located at the rear of the body portion of the socket plate in the space defined by the inturned edge 15 of said plate. The plates 13 of each hanger arm are provided with alined 65 perforations for a pivot pin or trunnion 16, which is adapted to be inserted in place after the extremity of the corresponding hanger arm has been passed through the slots. When the pivot pin has been placed 70 in position in the hanger arm, it is adapted to be seated at the respective ends thereof in seats 17 which are formed by bending outward the metal of the socket plate at the sides of the slots 14. 75

My invention relates particularly to the means for holding each pivot pin 16 in the seat formed by the depressions 17. For this purpose, I employ a bridge piece 18 constituted by a stiff metal plate which is 80 provided, preferably near the lower end, with an extension 19. This extension is passed through a small slot 20 in the socket plate beneath the corresponding pivot pin, and is then riveted down at 21 from the 85 front of the socket plate so as to hold the bridge piece, rigidly in the position shown in Fig. 4. It will be observed that the bridge piece extends vertically across a depression 22, in which the intermediate part 90 of the pivot pin is located, and that while the bridge piece is positively connected with the socket plate only at a point beneath the pivot pin, the upper portion of the bridge piece has an edge surface 23 95 abutting the rear surface of the socket plate above the depression 22. The rear edge of the bridge piece is substantially flush with the marginal flange 15 of the socket plate, as shown in Fig. 4, so that when the handle 100 as a whole has been applied to the box the bridge piece will be effectively supported against the box wall. Its upper end portion will also receive the strain when the bail 10 is lifted in order to move the box, 105 for when this happens the transverse edge

portion 24 on the hanger arm abuts the front face of the socket plate at about the point 24^a (Fig. 4) which is supported by the edge 23 of the bridge piece. In this 5 manner the sheet metal socket plate is effectively prevented from collapse because the strain on the handle is directly transmitted through the bridge piece to the box wall.

It will be observed that in the particular 10 form shown, the pivot pin 16 does not extend through the bridge piece. At its forward edge, the latter is provided with a notch 25 considerably wider than the pivot pin, in which said pin is located. This construction has the advantage that in manufacturing the handle the bridge piece can be made to hold the pivot pin effectively in place even if the former occupies any of a number of different positions. In other 15 words, no great care in locating the hole 20 is necessary. This hole which receives the tongue or extension 19 on the bridge piece may be located either above or below, or to one side or the other of the particular 20 position shown in the drawing.

In any event, however, the riveted head on the bridge piece should preferably be located beneath the corresponding hanger arm where it will be practically invisible, 25 and will not mar the appearance of the handle in any way.

I do not limit myself in all aspects of the invention, however, to a construction in which the bridge piece does not surround the 30 pivot pin.

Without limiting myself to the precise construction shown, I claim:

1. In a casket handle or the like, the combination of a socket plate having slots, an 40 arm having a forked end passing through said slots, a pivot pin extending through the forked end of the arm and securing it against withdrawal from the plate, a member at the rear of the plate directed transversely with respect to said pivot pin for 45 preventing rearward movement thereof, and means of connection between said member and said plate located at a point beneath the arm when the latter is in the pendant 50 position; substantially as described.

2. In a casket handle or the like, the combination of a socket plate having slots, a bail having a forked end passing through said slots, a pivot pin extending through the forked end of the bail and securing it against withdrawal from the plate, a member at the rear of the plate directed transversely with respect to said pivot pin for preventing rearward movement thereof, and 55 means located at a point beneath the bail for locking said member to the plate, said locking means comprising a tongue or extension on said member passing through and riveted in an opening in the socket plate; substantially 60 as described.

3. In a casket handle or the like, a socket plate having parallel slots, a forked arm having plates passing through said slots, a pivot pin extending through said plates, at the rear of the socket plate, and a bridge 70 member riveted to the socket plate and engaging said pivot pin to prevent rearward movement thereof; substantially as described.

4. In a casket or like handle, the combination of a socket plate, an arm having side walls passing partially through said socket plate, a pivot pin extending through the arm at the rear of the plate, said plate provided at the rear thereof with a depression in which said pivot pin is received intermediate the side walls of the arm, a retaining piece for said pivot pin passing across said depression, and means for connecting said retaining piece directly with the front wall of the socket plate at a point located behind the arm when the latter is in the pendant position; substantially as described. 75 80 85

5. In a casket handle or the like, a socket plate having parallel slots and having a depressed portion adjacent said slots forming a seat at the rear face of the plate, a bail having a forked end passing through said slots, a pivot pin passing through the forked end of the bail and located in said seat, a bridge piece extending vertically across the pivot pin and said seat to confine the former in the latter, said bridge piece having a bearing on the plate above said seat and another bearing on the plate below said seat, and a part on said bridge piece extending through an opening in the socket plate and riveted therein, said part being located behind the bail when the latter is in the pendant 90 95 100 position; substantially as described.

6. In a casket handle or the like, the combination of a socket plate, a bail having an end passing through said socket plate, a pivot pin passing through the bail at the rear of the socket plate to secure it against withdrawal from said plate in a forward direction, said socket plate having a depression at the rear thereof in which said pivot pin is located, a bridge member at 105 110 115 the rear of the socket plate for confining said pin in said depression, said bridge member consisting of a metal piece presented edgewise toward the rear surface of the socket plate and bearing thereon, and means of connection between said bridge member and the front wall of the socket plate located beneath said depression and at a point which is situated back of the bail when the latter is in the pendant position; substantially 120 125 as described.

7. In a casket handle or the like, a socket plate having parallel slots, a forked plate presenting parallel portions passing through said slots, a pivot pin extending through 130

said parallel portions at the rear of the socket plate, the latter being provided at the rear with a depression for seating said pin, a bridge piece at the rear of the plate bearing at one edge against the rear surface of the plate on opposite sides of said depression, and rigid means of connection be-

tween said bridge piece and the socket plate located at a point remote from said depression; substantially as described.

10

In witness whereof, I have hereunto set my hand, this 28th day of June, 1916.

ALBERT A. PAGE.
